UNITED STATES PATENT OFFICE.

OSCAR JUNGGREN, OF SCHENECTADY, NEW YORK, ASSIGNOR TO GENERAL ELECTRIC COMPANY, A CORPORATION OF NEW YORK.

ELASTIC-FLUID TURBINE.

Application filed July 27, 1923. Serial No. 654,262.

To all whom it may concern:

Be it known that I, OSCAR JUNGGREN, a citizen of the United States, residing at Schenectady, in the county of Schenectady, 5 State of New York, have invented certain new and useful Improvements in Elastic-Fluid Turbines, of which the following is a specification.

The present invention relates to elastic 10 fluid turbines in which the elastic fluid is withdrawn from the turbine at an intermediate stage, reheated, and returned again to the next lower stage of the turbine. This is ordinarily termed reheating between 15 stages.

In turbines of considerable output, the volume of elastic fluid to be withdrawn and returned again to the machine is large, which means that conduits of considerable 20 size are required to handle it, and one object of my invention is to provide an improved construction and arrangement whereby conduits for the withdrawal of the elastic fluid from the turbine and its return to 25 the turbine are provided without materially increasing the length of the machine.

Also, in such turbines, since the elastic fluid is withdrawn from one stage, reheated, and returned to the next lower stage, there 30 is a considerable difference in temperature between these two stages which means that there will be considerable difference in the amount of expansion, and a further object 35 of my invention is to provide an improved construction and arrangement which will permit of unequal expansion of the parts without there being set up stresses of an unduly large value.

For a consideration of what I believe to 40 be novel and my invention, attention is directed to the accompanying description and the claims appended thereto.

In the drawing, the figure is a side elevation, partly in section of a turbine structure 45 embodying my invention.

Referring to the drawing, 1 indicates the turbine casing and 2 the shaft upon which are mounted the turbine bucket wheels 3. 50 At 4 is indicated the admission conduit through which elastic fluid is supplied to the turbine. The low pressure end of the turbine is not illustrated in the drawing, only so much of the machine being shown as is required to illustrate my invention. The

turbine casing is divided into stages by the 55 nozzle diaphragms 5, there being a single wheel in each stage in the present instance. The elastic fluid is withdrawn from the stage indicated at 6, reheated, and then returned to the next lower stage indicated at 7. 60

Surrounding the turbine casing adjacent to stage 6, are walls 8, 9 and 10 which define an annular chamber 11 which communicates with stage 6 through passages 12 and surrounding the turbine adjacent to stage 7 are walls 13 and 14 which define with wall 10 an annular chamber 15 which communicates with stage 7 through passages 16. Walls 9 and 14 are integral with each 70 other and with the turbine casing and form in substance a part of the turbine casing. Chamber 11 is made of sufficient size to handle the volume of elastic fluid from stage 6 and leading from it is a conduit or discharge passage 17 through which the elastic fluid is conveyed to the reheater. Likewise chamber 15 is made of sufficient size to handle the reheated elastic fluid which is conveyed to it through conduit or inlet passage 18 which communicates therewith. 75

Wall 8 is in the form of an axially extending ring having an enlarged end 19 in which the passages 12 are formed, such passages being positioned and curved so as to receive the elastic fluid discharged from the buckets of the bucket wheel in stage 6 and direct it into chamber 11. The left hand end of wall 8 is seated in the turbine casing as indicated at 20 and carries the diaphragm 85 which it surrounds. It is fixed against axial movement by shoulders 21 and is locked in place by a wedge shaped key 22. The right hand end of ring 8 is locked to wall 10 and the diaphragm 23 between stages 6 and 7 by tongue and groove connections 24 and 25. 90

A suitable amount of clearance is provided between the adjacent, axially-extending surfaces of tongue and groove connections 24 and 25 so as to permit free relative 95 radial expansion between the parts.

Wall 10 is joined to wall 13 by webs or plates 26 which define with the adjacent surfaces of walls 10 and 13, the passages 16 which are shaped to form nozzles for directing the elastic fluid from annular chamber 15 to the buckets on the bucket wheel in stage 7. Or viewed from another aspect, walls 10 and 13 may be considered as a sin- 100 105

gle integral structure in which are formed the nozzle passages 16. Wall 13 is fixed to the turbine casing at the end toward the low pressure end of the machine by an annular tongue and groove connection as indicated at 27, and carries the diaphragms which it surrounds. At 27^a is a wedge shaped locking key for fastening the tongue in the groove. The outer edge of wall 10 fits in 10 a groove 28 at the juncture of walls 9 and 14, there being a suitable amount of clearance in a radial direction as indicated at 29 to permit of relative expansion and contraction of the parts.

15 At 30 is an annular chamber which receives elastic fluid from the turbine stage in advance of stage 6 by way of passages 31 and 32 and delivers it through a passage 33 to any desired point outside the turbine. 20 The elastic fluid thus extracted from this stage may be used for heating the liquid used in the boilers which supply the elastic fluid to the turbine. Passage 31 may be in the form of a number of spaced holes in 25 ring 8. Passage 32 may be formed by spacing the adjacent diaphragm walls from ring 8. Such spacing may be effected by means of suitable pins 34.

With the foregoing arrangement it will 30 be seen that both the wall 8 and the wall structure comprising walls 10 and 13 are free to expand and contract in a radial direction, thereby avoiding danger of buckling of the parts or the setting up of stresses in 35 the turbine casing.

The wall 10 is a partition wall between 40 chambers 11 and 15 and is preferably arranged substantially in line with diaphragm 23 between stages 6 and 7. The elastic fluid is removed on the high pressure side of wall 10 and returned on the low pressure side of it. The bucket wheel in stage 7 is made of greater diameter than the bucket wheel in 45 stage 6. This brings nozzle passages 16 outside passages 12 and 14 then arrange passages 16 and 12 so they are substantially concentric, both surrounding stages 6 and 7. By this means I am enabled to provide for the removal of the elastic fluid from the one 50 stage of the turbine and its return to the next lower stage without increasing to any great extent the axial length of the machine.

When the turbine is in operation, the elastic fluid discharged from the buckets of the 55 bucket wheel in stage 6 is conveyed by the annular ring of passages 12 to annular chamber 11 and from there by way of conduit 17 to the reheater (not shown). After being reheated the elastic fluid is returned through 60 conduit 18 to annular chamber 15 from whence it flows through the ring of nozzle passages 16 to the buckets on the bucket wheel in stage 7. The temperature of the elastic fluid in chamber 15 is thus very 65 much higher than that in chamber 11 which

means that the respective portions of the turbine directly adjacent to chambers 11 and 15 are subjected to greatly different temperatures. By my invention these adjacent portions are permitted to expand and contract radially independently of each other. At the same time, however, they are firmly held against movement in an axial direction.

In accordance with the provisions of the 75 patent statutes, I have described the principle of operation of my invention, together with the apparatus which I now consider to represent the best embodiment thereof, but I desire to have understood that the apparatus shown is only illustrative and that the invention may be carried out by other 80 means.

What I claim as new and desire to secure by Letters Patent of the United States, is: 85

1. In an elastic fluid turbine, a casing comprising walls which define adjacent annular chambers which surround the casing, certain of such walls extending in an axial direction and being fixed at one end and free 90 to expand radially at the other end, and means defining sets of passages in said axially-extending walls which connect the chambers to the interior of the turbine casing.

2. In an elastic fluid turbine, a casing comprising walls which define adjacent annular chambers which surround the casing, certain of such walls extending in an axial direction and being fixed at one end and free to expand radially at the other end, diaphragms supported by such axially-extending walls, said diaphragms defining stages in the turbine, and means defining 95 passages which connect adjacent stages to said annular chambers.

3. In an elastic fluid turbine, a rotor having rows of blades, a casing having at one point a part of a diameter greater than the adjacent parts whereby there is provided a surrounding enlarged portion, a wall dividing the casing into two sections and the enlarged portion into adjacent chambers, means defining passages for directing elastic fluid from a bucket row to one of said chambers, and means defining passages for directing elastic fluid from the other chamber to another bucket row, whereby, through 100 said chambers, elastic fluid may be withdrawn from the turbine, reheated, and returned to the turbine.

4. In an elastic fluid turbine, a casing comprising walls which define adjacent annular chambers which surround the casing, certain of such walls extending in an axial direction and being fixed at one end and free to expand radially at the other end, diaphragms supported by such axially-extending walls, said diaphragms defining stages in the turbine, and means defining 105 sets of passages which connect adjacent 110 chambers.

stages to said annular chambers, said sets of passages being located one radially outside the other.

5. In an elastic fluid turbine, a casing having at one point a part of a diameter greater than the adjacent parts whereby there is provided an enlarged surrounding portion, diaphragms dividing the casing into stages, walls which divide the casing into 10 two sections and which form with such enlarged portion two annular chambers, passages in said walls which connect one of the chambers with the last stage of the one turbine section, and passages in said walls 15 which connect the other of said chambers with the first stage of the other turbine section, the passages for the respective stages being concentric with each other.

6. In an elastic fluid turbine, a casing 20 having at one point, a part of a diameter greater than the adjacent parts whereby there is provided a surrounding enlarged portion, diaphragms dividing the casing into stages, walls associated with said part 25 of greater diameter which form therewith two annular chambers, said walls forming supports for the diaphragms which they surround, and passages in said walls which connect the chambers with adjacent turbine 30 stages, the adjacent ends of said walls being free to expand and contract radially.

7. In an elastic fluid turbine, a casing 35 having at one point a part of a diameter greater than the adjacent parts whereby there is provided a surrounding enlarged

portion, diaphragms dividing the casing into stages, axially-extending walls fixed to the casing adjacent the inner edges of the enlarged portion and projecting toward each other, said walls forming supports for 40 the diaphragms which they surround, a radially-extending wall associated with said axially-extending walls and serving to divide the enlarged casing portion into two chambers, and passages in said walls which 45 connect said chambers with adjacent turbine stages.

8. In an elastic fluid turbine, a casing having at one point a part of a diameter greater than the adjacent parts whereby 50 there is provided a surrounding enlarged portion, diaphragms dividing the casing into stages, axially-extending walls fixed to the casing adjacent the inner edges of the enlarged portion and projecting toward 55 each other, said walls forming supports for the diaphragms which they surround, a radially-extending wall fixed to the free end of one of said axially-extending walls and having a tongue and groove connection with 60 the other axially-extending wall and with the wall of the enlarged portion, radial clearance being provided to permit expansion and contraction of the parts, and passages in said walls which connect the chambers with adjacent turbine 65 stages.

In witness whereof, I have hereunto set my hand this 26th day of July, 1923.

OSCAR JUNGGREN.
